BUILDING

Lee N. Romano, 1130 S. Delphia, Park Ridge, Ill.

Filed Oct. 28, 1963, Ser. No. 77,165

Term of patent 14 years

(Cl. D13—1)

FIG. 1 is a front elevational view of a building embodying my new design, the dominant features thereof being shown in solid line representation;

FIG. 2 is a side elevational view of the same; and

FIG. 3 is a sectional view taken along lines 3—3 of FIG. 1 and in the direction indicated.

The center of the building is broken away in FIGS. 1 and 2 to indicate indeterminate length.

I claim:

The ornamental design for a building, substantially as shown and described.
